UNITED STATES PATENT OFFICE.

HARVEY THATCHER, OF MAROA, ILLINOIS.

WIND-OPERATED TOY.

1,260,833.

Specification of Letters Patent. Patented Mar. 26, 1918.

Application filed July 20, 1917. Serial No. 181,768.

To all whom it may concern:

Be it known that I, HARVEY THATCHER, a citizen of the United States, residing at Maroa, in the county of Macon, State of Illinois, have invented a new and useful Wind-Operated Toy; and I do hereby declare the following to be a full, clear, and exact description of the invention, such as will enable others skilled in the art to which it appertains to make and use the same.

The present invention relates to a wind operated toy, and has for its object to provide a device of this character which embodies novel features of construction whereby jointed figures are caused to move in a life-like manner by the rotation of a wind wheel.

Further objects of the invention are to provide a toy of this character which is comparatively simple and inexpensive in its construction, which can be readily mounted in position to be operated by the wind, which can be readily taken apart and put together, and which will afford an endless amount of amusement for children.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Fig. 1 is a side elevation of a wind operated toy constructed in accordance with the invention, portions being broken away and shown in section to illustrate more clearly the details of construction.

Fig. 2 is a transverse vertical sectional view on the line 2-2 of Fig. 1.

Fig. 3 is a similar view taken on the line 3-3 of Fig. 1.

Fig. 4 is a detail view of the wind wheel and the end of the shaft to which it is attached, portions of the wind wheel being broken away.

Figs. 5 and 6 are detail views showing a modification which is designed for attaching a device to the filling sleeves of automobile radiators.

Corresponding and like parts are referred to in the following description and indicated in all the views of the drawings by the same reference characters.

Specifically describing the present embodiment of the invention, the reference numeral 1 designates a supporting post which is provided at its upper end with a pivot pin 2 upon which a revolving and horizontally disposed platform 3 is mounted. A pair of spaced standards 4 project upwardly from the revolving platform 3, said standards being provided at their upper ends with vertical slots 4^a for the reception of a horizontally disposed shaft 5. This shaft is provided with a pair of crank portions 5^a which are offset upon opposite sides thereof, said crank portions pivotally engaging the arms 6 of jointed figures A. The legs 7 of the jointed figures are rigidly secured to the platform 3 and pivotally connected at 7^a to the body 8, the arms 6 being similarly connected to the body at 6^a. With this arrangement it will be obvious that as the crank shaft revolves a life-like motion will be imparted to the jointed figure.

A wind wheel 9 is fitted upon one end of the crank shaft 5, being preferably removably applied thereto, and being locked with the shaft so that the shaft and wheel will rotate together. For this purpose the end portion of the shaft is shown as provided with a crimped portion 10 which forms a shoulder against which the wind wheel 9 fits. A U-shaped sliding latch 11 straddles the hub of the wind wheel, the arms thereof being received within suitable guides 12, and the outer arm terminating in a finger piece 13, while the opposite arm is provided with a finger 11^a adapted to engage and interlock with the crimped portion 10 of the crank shaft. When the member 11 is moved outwardly into inoperative position and the finger 11^a disengaged from the crimped shoulder 10 the wind wheel can be disengaged from the shaft or placed in position thereon. However, when the member 11 is moved inwardly to bring the finger 11^a into engagement with the crimped shoulder 10 the wind wheel is locked in position and at the same time made rigid with the shaft so that the wheel and shaft will rotate together. The end of the platform 3 remote from the wind wheel 9^a is provided with a vane 14 which is arranged in the vertical plane of the shaft 5 and standards 4 and serves to revolve the platform 3 and hold it in position with the wheel 9 facing the wind.

The crank shaft 5 is held in position within the slots 4^a in the upper end of the stand-

ards 4 by means of swinging latches 15, the swinging ends of the latches being doubled to fit around and straddle the standards, and being transversely slotted at 15^a to receive the shaft 5. Side arms 15^b at the opposite ends of the swinging latch members 15 extend downwardly along opposite sides of the standards 4 and are pivotally connected thereto at 16. The shaft 5 is provided with shoulders 17 which engage the sides of the doubled ends of the swinging latch members 15 to hold the shaft against longitudinal sliding movement, and when the latch members are in operative position 15 the slotted portions 15^a thereof receive the shaft and hold it in position within the notched ends 4^a of the standards 4.

The arms 6 of the jointed figure may have the free ends thereof notched at 6^b to receive the crank portions 5^a of the shaft 5, and swinging latch members 17' similar to the before mentioned latch members 15 may be provided for engaging the shaft and holding it in position within these notches. If 25 desired, the legs 7 of the jointed figures may be provided at the feet thereof with T-shaped heads 18 adapted to be inserted through slots 19 in the base 3 to admit of the figure being placed in position or removed therefrom when turned about a vertical axis into a position at right angles to that which it normally occupies. When the jointed figure is turned into normal position, namely into a plane at right angles to the 35 shaft 5, the T-shaped head 18 of the foot thereof will interlock with the slot 19 to hold the jointed figure securely in position. The figures are thus constructed in such a manner that they can be readily placed in 40 position or removed therefrom, thereby enabling a variety of figures to be used and greatly enhancing the amusement to be obtained from the toy by enabling different figures to be substituted at intervals of time.

45 In pivotally mounting the platform 3 upon the pivot pin 2, any suitable construction may be provided, although in the present instance this pivot pin is shown as surrounded by a sleeve 20 which fits within a substantially semi-circular bend or twist 3^a at the middle portion of the platform 3, the opposite side of the sleeve being engaged by a hooked latch 21 which is pivotally connected to the platform at 22. The swinging 50 end of the hooked latch has a resilient formation so as to spring around the sleeve 20 and lock the parts in operative position.

A slight modification is shown by Figs. 5 and 6, in which the platform is constructed 55 for attachment to the filling sleeve at the top of an automobile radiator, said sleeve being indicated at R. In this instance the platform would not rotate, but would be clamped rigidly in position. The platform 65 3^b, which is constructed substantially as in

the previous instance, is provided with a twisted semi-circular portion 3^c adapted to fit around one side of the radiator sleeve 4, the other side of the radiator sleeve being engaged by a hooked latch 21^c which is pivotally connected at 22^c to the platform, the hooked swinging end thereof having a resilient formation so as to spring around the sleeve R and lock the parts in position. 70

Having thus described the invention, what I claim as new and desire to secure by Letters Patent, is:—

1. A wind operated toy including a supporting post, a horizontal platform revolvably mounted upon the post, a pair of standards projecting upwardly from the platform, a horizontal shaft journaled in the standards and formed with a crank portion, said shaft having a crimped shoulder at a point toward one end thereof, a wind wheel fitted upon the said end of the shaft, a U-shaped latch member straddling the hub of the wind wheel and provided with a finger adapted to engage the crimped shoulder to lock the wind wheel in position upon the shaft, a jointed figure mounted upon the platform and operatively connected to the crank portion of the shaft, and a vane applied to the platform for holding the wind wheel to the windward. 80

2. A wind operated toy including a supporting post, a horizontal platform revolvably mounted upon the post, a pair of standards projecting upwardly from the post and having the upper ends thereof slotted, a horizontal shaft fitted in the slotted upper ends of the standards and formed with a crank portion, swinging latch members pivotally mounted upon the standards and having the swinging ends thereof doubled to straddle the standards, said doubled ends of the latch members being transversely slotted to receive the horizontal shaft and hold it in position within the slotted upper ends of the standards, shoulders on the shaft for engaging the latch members to hold the shaft against longitudinal movement, a jointed figure mounted upon the platform and operatively connected to the crank portion of the shaft, a wind wheel applied to the shaft, and a vane applied to the platform for holding the wind wheel to the windward. 95

3. A wind operated toy including a supporting post, a horizontal platform revolvably mounted upon the post, a pair of standards projecting from the platform, a horizontal shaft journaled in the standards and provided with a crank portion, a jointed figure provided with arms and feet, the feet having a detachable and interlocking connection with the platform, while the arms have the ends thereof slotted to receive the crank portion of the shaft, a swinging latch member pivotally mounted upon the arms 100

and having the swinging end thereof doubled to straddle the arms, said doubled end of the latch member being transversely slotted to receive the crank portion of the shaft 5 and hold it in position within the slotted end of the arms, a wind wheel applied to the shaft, and a vane applied to the platform for holding the wind wheel to the windward.

10 4. A wind operated toy including a supporting post, a horizontal platform revolv- bly mounted upon the post and provided with a slot, a pair of standards projecting upwardly from the platform, a horizontal 15 shaft journaled in the standards and pro- vided with a crank portion, a jointed figure formed with arms and legs, the legs termi- nating in a T-shaped head adapted to interlock with the before mentioned slot in 20 the platform, while the arms are slotted to receive the crank portion of the shaft, a latch member upon the arms for holding the shaft within the slotted end thereof, a

wind wheel applied to the shaft, and a vane applied to the platform for holding the 25 wind wheel to the windward.

5. A wind operated toy including a vertical support, a horizontal platform pro- vided with a semicircular jaw portion re- ceiving one side of the vertical support, a 30 hooked latch member pivotally mounted upon the platform and having a resilient hooked end which springs around the oppo- site side of the vertical support, a horizon- tal shaft carried by the platform and pro- vided with a crank portion, a jointed figure mounted upon the platform and operatively connected to the crank portion of the shaft, and a wind wheel fitted upon the shaft.

In testimony whereof I have signed my 40 name to this specification in the presence of two subscribing witnesses.

HARVEY THATCHER.
